UNITED STATES PATENT OFFICE.

LOUIS C. JABLESNIK, OF BERGENFIELD, NEW JERSEY.

SCABBARD-HANGER.

1,302,799.

Specification of Letters Patent.

Patented May 6, 1919.

Application filed August 3, 1918. Serial No. 248,173.

To all whom it may concern:

Be it known that I, LOUIS C. JABLESNIK, a citizen of the United States, residing at Bergenfield, in the county of Bergen and State of New Jersey, have invented a new and useful Scabbard-Hanger, of which the following is a specification.

The device forming the subject matter of this application is a scabbard hanger and, to 10 the end that the objects of the invention may be understood clearly, the accepted order will be departed from slightly, in this specification, the figures of the drawing and parts of the device being described first, and the 15 objects being stated when the description has proceeded far enough so that these objects may be appreciated readily.

In the accompanying drawings:—

Figure 1 shows in front elevation, a known 20 form of belt, a portion of which is adapted to be used with the belt shown in Fig. 2, through the instrumentality of the device forming the subject matter of this application; Fig. 2 shows in front elevation, a belt 25 which is of known form, saving for the fact that a part of the structure shown in Fig. 1 has been assembled therewith by means of the device hereinafter claimed; Fig. 3 is a section on the line 3—3 of Fig. 2; and Fig. 4 30 is a perspective showing a modification.

The numeral 1 denotes a body encircling belt issued to officers in the army of the United States and adapted to support a sword or saber. A slide 2 is mounted on the 35 belt 1 and is provided with an opening 3 wherein is located a frame 4, engaged with the belt 1 and provided at its lower end with an outstanding loop 5. A U-shaped hanger 6 is provided, the same including an outer 40 arm 7 having a bend 8 at its upper end and including an inner arm 9 coöperating with the bend, the bend being engaged detachably with the loop 5. At their lower ends, the arms 7 and 9 of the hanger 6 merge into a 45 bearing 10. The outer arm 7 of the outer arm 6 carries a hook 11. An eye 12 is mounted 50 to swing in the bearing 10 and carries diverging straps 14, fashioned at their lower ends into loops 15, held at adjusted lengths by means of buckles 16, the loops supporting 55 snaps 17. It is obvious that the hanger 6 and parts carried thereby form a means whereby a saber or sword may be suspended from the belt 1.

The numeral 18 marks a body encircling belt which has replaced recently, the belt 1.

The belt 18 is provided adjacent one edge with eyes 19, adapted to carry a canteen, a holster, a first aid pouch and the like. It will be obvious, however, that no provision is 60 made, in connection with the belt 18 whereby a sword or saber may be suspended therefrom.

Having progressed thus far with the description, it may be stated that it is the object of this invention to provide a simple but inexpensive means whereby the hanger 6 and parts carried thereby, as shown in connection with the belt 1, may be mounted on the belt 18, thus adapting the belt 18 to carry a 70 sword or saber and at the same time rendering it unnecessary to cast aside as useless, the hanger 6, which, formerly, in connection with the belt 1, has afforded a useful and satisfactory means for supporting a saber. 75

In carrying out the present invention, there is provided a U-shaped member 20 comprising a base bar 21 supplied at its ends with upright hooks 22 the depending portions of which are provided with inwardly 80 extended approaching fingers 23. A pendant 24 made of leather or other suitable material is bent upon itself around the base bar 21 and is stitched as shown at 25 to form a socket 26 wherein the base bar is located. 85 An upstanding guard 27, made of leather or the like, extends to the rear of the hooks 22 and is held upon the pendant 24 by means of the stitching 25 hereinbefore alluded to. The socket 26 is provided with slots 28, receiving eyes 29 pivotally mounted on the base bar 21 of the U-shaped member 20 and located at the upper ends of depending arms 30, carrying a forwardly presented loop 31. 90

The hooks 22 of the member 20 may be 95 engaged in the eyes 19 of the belt 18, the fingers 23 preventing an accidental detachment of the hooks from the eyes. The U-shaped hanger 6 and attendant parts may be engaged with the loop 31, thus the hanger 100 and its parts, having been removed from the belt 1, may be assembled with the belt 18. The invention, obviously, affords a simple means whereby the hanger 6 and coöperating parts may be detached from the belt 1 105 and assembled with the belt 18, thus rendering the latter belt useful to officers and other persons called upon to carry a saber.

In Fig. 4 of the drawings, wherein the modified form of the invention is shown, 110 parts hereinbefore described are designated by numerals previously used, with the suffix

"a". The modification consists in fashioning the arms 30^a integrally with the base bar 21^a of the U-shaped member 20^a thus dispensing with the eye 29 and adapting the structure for the use of those who do not care to take advantage of pivotal movement afforded by the mounting of the eyes 29 on the base bar 21.

Having thus described the invention, what is claimed is:—

- 10 1. A device for adapting a scabbard hanger to a belt, comprising a U-shaped member including a base bar having upright forwardly extended hooks at its ends, the base bar carrying depending arms connected by a loop.
- 15 2. A device for adapting a scabbard hanger to a belt, comprising a U-shaped member including a base bar having upright forwardly extended hooks at its ends, the hooks ter-

minating in approaching inwardly extended fingers, the base bar carrying depending arms connected by a forwardly presented loop.

3. A device for adapting a scabbard hanger to a belt, comprising a pendant provided with a socket having slots; a U-shaped member including a base bar located in the socket, and upright hooks at the ends of the base bar, the base bar carrying depending arms located in the slots, the arms being connected by a forwardly presented loop.

In testimony that I claim the foregoing as my own I have hereto affixed my signature in the presence of two witnesses.

LOUIS C. JABLESNIK.
